UNITED STATES PATENT OFFICE.

MICHAEL L. SUTTON AND DONALD HEYER, OF HOLLYWOOD, CALIFORNIA.

REAMER.

Application filed May 6, 1924. Serial No. 711,426.

To all whom it may concern:

Be it known that we, MICHAEL L. SUTTON and DONALD HEYER, citizens of the United States, residing at Hollywood, in the county 5 of Los Angeles, State of California, have invented certain new and useful Improvements in Reamers; and we do hereby declare the following to be a full, clear, and exact description of the invention, such as 10 will enable others skilled in the art to which it appertains to make and use the same.

This invention relates to new and useful improvements in tools, and particularly to reaming tools.

15 One object of the invention is to provide a reaming tool which has novel means for adjusting the cutters for differently sized openings, and novel means for holding the cutters in such adjusted positions.

20 Another object is to provide an adjusting means for moving the cutters inwardly or outwardly, and which is operable without permitting the cutters to become disengaged from the holder.

25 Other objects and advantages will be apparent from the following description when taken in connection with the accompanying drawing.

In the drawing:

30 Figure 1 is an elevation of a reaming tool made in accordance with the present invention.

Figure 2 is a vertical longitudinal sectional view through the tool, one of the 25 blades being removed, and shown in dotted lines.

Figure 3 is a transverse section on the line 3—3 of Figure 2, one of the blades being removed.

40 Figure 4 is a transverse sectional view on the line 4—4 of Figure 2, one of the blades being removed.

Referring particularly to the accompanying drawing, 10 represents the cutter holder 45 which is in the form of a tube with its opposite ends reduced in diameter and externally threaded, as shown at 11 and 12, respectively. Formed integrally with the holder, and arranged centrally therewithin, 50 is a wall 13, having a central opening 14, to which reference will be made later herein. Formed longitudinally in the wall of the tubular holder 10, and with slight spiral inclinations, are the slots 15, the outer ends 55 of which extend into the reduced end portions of the holder, while the inner ends are

connected by the longitudinal grooves 16 formed in the wall 13.

Each of the cutters is in the form of an elongated blade 17 having its ends beveled, 60 as shown at 18, and with the angular recess 19 in its groove entering edge. Into this recess enters the wall 13, which the portions at each end of the recess pass into the slots 15. The beveled end portions of the cutter extend 65 out onto the reduced ends of the holder.

Disposed longitudinally through the holder, and through the opening 14, of the wall, 13, is a spreader bar or shaft represented as a whole by the numeral 20, the 70 ends of said bar being reduced in diameter, as shown at 21 and 22, the former being threaded, while the latter is provided with a smooth exterior. The intermediate portion of the bar 20 is cylindrical, at 20', and 75 it is this portion which is loosely received in the bore of the wall 13. The portion of the bar, between this portion 20', and the threaded end 21 is tapered toward said threaded end, as shown at 22', for engagement 80 with the correspondingly tapered or inclined portion of the inner longitudinal face of the cutter, as shown at 23. The portion between the other end of the cylindrical portion 20', and the reduced end 22 is 85 tapered at 22'', in the direction of the cylindrical portion. The larger ends of these tapered portions produce shoulders 24 and 25, respectively. It will be noted that the portion of the inner longitudinal face of 90 the cutter, at the other side or end of the recess 19, is inclined to correspond to the taper of the portion 22', and slidably contacts therewith, as clearly seen in Fig. 2.

Threaded on the end 21, of the spreader 95 bar 20, is a nut 26, the inner end of which has a peripheral outstanding flange 27, which bears against the adjacent end of the cutter holder 10, when screwed home. The outer end of the nut 26 is provided with 100 wrench faces 26', to permit the nut to be turned. Slipped on the stem of the nut 26 is a nut 28, which engages with the threaded end of the holder 10, to maintain the nut 26 tightly against the said end of the holder. The flange of the nut 28 is beveled to overlie 105 or bear against the beveled end of the cutter 17, to maintain said end of the cutter within the slot of the holder. Threaded onto the other end of the holder 10 is a similar nut 29, the stem 22 being received centrally therethrough, as seen in the drawing. The 110

flange of this nut 29 is beveled to bear against the beveled ends of the cutters, to retain said ends in the slots.

When it is desired to move the cutters outwardly, as when a larger opening is to be reamed, the nuts 28 and 29 are backed off sufficiently to partially release the beveled ends of the cutter blades, when the operator rotates the nut 26 inwardly against the adjacent end of the holder 10, with the result that the spreader bar 20 will be drawn toward that end of the holder causing its tapered portions 20' and 22' to ride on the inclined faces of the cutter blades to push said blades outwardly through the slots 15. When the blades have been moved out to the desired distance, the nut 28 and the nut 29 are screwed inwardly until their beveled flanges firmly engage with the beveled ends of the cutter blades, whereby the blades are firmly held in their adjusted position.

When the cutter is to be adjusted for a smaller opening, the nuts 28 and 29 are again backed off, and the nut 26 turned outwardly, which permits the spreader bar to move toward the other end of the holder 10, whereupon the inclined faces of the cutters will slide down on the tapered portions 20' and 22', and move into the slots 15. Upon turning the nuts 28 and 29 toward the ends of the holder 10, the beveled flanges of

said nuts will bear against the beveled ends of the cutter blades, and firmly hold the blades in position.

What is claimed is:

An expanding reamer including a longitudinally slotted holder having an intermediate transverse wall in each slot, cutter blades disposed in the slots of the holder and having inner inclined faces and outer beveled ends, the intermediate portion of the inner edge of each cutter blade having an elongated recess receiving a transverse wall therein and by which the blade is positively guided in its radial movements, means engaged on the ends of the holder and engaging with said beveled ends of the cutter blades, a tapered spreader bar movable within the holder and engaged with the inclined faces of the cutter blades at opposite ends of the said recesses, and a nut engaged on one end of the spreader bar and bearing against the adjacent end of the holder for moving the bar to adjust the blades through the slots of the holder, said nut being retained in position by one of said holder engaged means.

In testimony whereof, we affix our signatures.

MIKE L. SUTTON.
DONALD HEYER.
